UNITED STATES PATENT OFFICE.

EDGAR J. MARTEL, OF LACONIA, NEW HAMPSHIRE.

OPERATING CONTROL DEVICE.

Application filed July 12, 1920. Serial No. 395,652.

To all whom it may concern:

Be it known that I, EDGAR J. MARTEL, a citizen of the United States, and a resident of Laconia, in the county of Belknap and State of New Hampshire, have invented an Improvement in Operating Control Devices, of which the following description, in connection with the accompanying drawings, is a specification, like characters on the drawings representing like parts.

This invention relates to controlling devices for motor vehicles and particularly to the switches controlling the electric currents and parts operated thereby.

15 In the drawings of the particular embodiment of my invention illustrated and described in this application,

Fig. 1 is a plan of my invention shown mounted on the quadrant of the steering post of an automobile;

Fig. 2, a plan of the base of the housing or case, with the cover removed;

Fig. 3, a side elevation of the control with the housing partly broken away;

25 Fig. 4, a vertical cross section on the line 4—4, Fig. 2;

Fig. 5, a diagrammatic plan of the wiring in the base, connecting the several terminals and switches;

30 Fig. 6, a plan of the rear signal control case, part of the housing being broken away;

Fig. 7, a similar figure with the cover removed; and

Fig. 8, a vertical section on the line 8—8, 5 Fig. 7.

Referring first to Figs. 1 to 3, my improved control, as illustrated, comprises a base member 1, with a cover 2 forming a housing, and adapted to be secured by any suitable means to any convenient support, preferably to the quadrant 4 carrying the spark and gas levers 5 and 6 respectively.

By mounting the control as above noted, it is placed in the most convenient possible location for use by the driver, as he can thus operate the principal devices without releasing either hand from the steering wheel.

The controlling devices, herein Fig. 5, comprise a main ignition switch 7, a light switch 8, a horn or signal switch 9, and the light regulating switch 10, the latter switch adapted, as will be presently described, to furnish either a bright or dim light.

Referring particularly to Fig. 5, it will be noted that the base is shown provided with five terminals 12, 22, 26, 27, 32, which

may be of any desired type. Here these terminals are in the form of posts. Post 12 is connected by a wire *a* with a battery *b* and is the source of current. From post 12 a wire *c* leads to the contact 13, which, with the adjacent contact 14, form parts of the switch 7. This switch comprises a body 15, Fig. 2, slotted at 16 to receive the insulated contact block 17, which is long enough to overlie both the contacts 13 and 14 when the switch is closed. It is shown open in Fig. 2. The body 15 is guided and retained in its position by slots 18 at either end thereof which receive guide pins 19 in the base.

The wire *c* also connects the terminal 12 with the contact 20 through the medium of the wire *d*, contact 20 and the adjacent contact 21 being parts of the switch 8. This switch is shown in Fig. 2 open, but, when closed, supplies current for the usual headlights of the car.

From the contact 14 the wire *e* leads to the post 22 and thence to the ignition system 1, 80 not shown.

From the contact 21 a wire *f* leads to the contact 23 which, with the adjacent contacts 24 and 25 are parts of the switch 10. This switch, also like switch 7 in construction, is 85 adapted to connect the contacts 23 and 24, and when closed will furnish current by means of the line *i*, to post 26, and from thence to the lighting system *L*, not shown. When this switch is thrown as shown in 90 Fig. 2, to connect the contacts 23 and 25, current will be supplied by means of the line *g*, to terminal 27 and thence by means of the line *h* through the dimming device as a resistance 28 to the light not shown, *D*. 95

The line *c* also runs to a terminal 29 which, with its adjacent terminal 30, constitute part of the horn or signal switch 9 which is shown in Fig. 2 as open. This switch is operated by pushing it inwardly 100 against the spring 31, and when closed establishes a connection between the line *c* and line *j* to the post 32, thence by the line *k* to the horn *H*, not shown. In each case the contact block 17 is held down upon the contacts by a spring 33 secured to the switch body. The body of the horn switch 9 has, upon its (Fig. 2) left hand edge, a notch 34 which will engage the edge of the section 35 of the side of the housing and retain the switch closed and will thus provide a continuous blowing of the horn. The switch 10

is locked in desired position by the spring 36 mounted upon the base 1 and engaging notches 37 in the edge of the switch body.

Pivoted at either side of the base 1 by screws 37^a, shown in Fig. 2, dotted lines, is a U-shaped multiple locking member 38. The front bar 39 of this member is provided, see Fig. 4, with a series of notches 40 adapted respectively to engage the locking ends or pins 41, 42, 43, 44, of the several switch bodies and lock them, except the ignition switch, in either open or closed positions. The ignition switch can be locked in either open or closed position. This locking member 39 is pressed down into locking position by the bolt 45 of the lock 46 controlled by a suitable key.

Extended upwardly and laterally Fig. 3, from the cover of the housing is a horn like member 47 carrying a switch box 48 with a semi-transparent cover 49, which is thus positioned directly over the steering post. In this switch box, see Figs. 6, 7 and 8, is a post 50, the lower end of which is journaled in a bar 51 extended across the box, the upper end being journaled in the cover 49. This post carries an operating lever 52 upon the outside of the cover. The post also carries a switch blade 53 adapted, as rotated, to engage either of the pairs of contacts 54 and 55, 56 and 57, 58 and 59, 60 and 61, as the case may be. From the contacts 54, 57, 59, 61, wires 7 lead to the ignition system, not shown. Wires *m* also lead from the contacts 55, 56, 58, 60, to different operating signals, not shown.

As indicated in Fig. 7, the wire *m* from contact 55 leads to any desired backing signal, wire *m* from contact 56 leads to a signal indicating that the driver is to turn to the right, wire *m* from contact 58 leads to the stop signal, and the corresponding wire from contact 60, leads to the signal indicating that the driver is to turn to the left. It will be noticed that the cover of the switch box is illuminated by a lamp 61 connected by a wire 62 with the ignition system so that the driver can always see at night the position of the lever 52 for displaying the proper signal.

The switch control case as shown is compact in construction, with the switch handles varying somewhat in length according to the position of the switch upon the case, and it possesses a distinct advantage over any other construction of which I have any knowledge.

After one has driven a car for some time, the right and left hands become accustomed to the movement in opposite circular paths corresponding to the path of movement of the steering wheel and it is an advantage to have the switch control handles or bars so positioned as to move generally in the same directions as the wheel. The spark and gas

levers are an illustration of this desirable construction.

However, there is a serious objection to placing too many switch levers or handles either upon a quadrant or in any such general operative relation, owing to the likelihood of confusion in operating them, particularly at night; i. e., the danger of making a mistake in selecting the wrong lever. Hence, it would be objectionable to mount four switch levers corresponding to the switch levers or handles shown, upon a common fulcrum point, and all to be operated generally in a curvilinear path corresponding to the wheel rim.

To obviate this objection and at the same time to retain so far as possible the advantage of having the switches move generally in paths corresponding to those of the wheel rim, I have so arranged the switches that two of them, to wit, the ignition and light switches are operated by a lateral movement of the hand corresponding generally to the usual movement of the left hand with that portion of the wheel rim adjacent the driver's body, and which is commonly grasped by the left hand for steering purposes. The horn and light switches are operated by a forward and back movement of the hand corresponding generally to the path of movement of the adjacent portion of the wheel rim which would be toward or from the driver's body, and corresponding to the general movement of the left hand when the steering wheel is grasped at a point thereof at the left of and somewhat forward of the driver's body.

In this way I obtain the advantage of following in a general way the path of movement of the steering wheel to which the left hand is accustomed, and at the same time locate the switches sufficiently far apart and distinctively as to position, to avoid the danger of mistaking one switch for another when they are to be operated hurriedly. In the drawings, Fig. 1, the variation in the length of the switch handles is shown, but it will be obvious that the length of the switch handles, in practice, may be varied to any desired extent to bring these handles in position to be operated to best advantage in view of the facts above set forth.

All drivers of automobiles recognize the convenience of having the switch controls located in a convenient position above the steering wheel as distinguished from the location upon the steering post and at the front thereof, requiring a labored and more or less indefinite motion of the hand or finger to operate them. This permits easy operation of the frequently used switches without releasing control of the steering wheel. This same desirability of convenience is still further effected and realized

by the above location of the switch handles, having in mind also the direction of operation of the same and making it harmonize so far as possible with the general direction 5 of operating the wheel to which the hand is accustomed.

The illuminated signal case for the driving signals is a novel feature which is advantageously combined in the compact construction of the switch control case, and also conveniently located for operation in connection therewith, and also for observation. The illuminated dial facilitates driving at night and ensures the correct positioning of the signal lever relative to the several contacts for positive operation of the signals.

It will be obvious that my invention is not limited in all details to the illustrative embodiment herein shown and described.

Claims—

1. A switch control case for automobiles having switches therein and adapted to be positioned at one side of the steering post 25 and supported thereby, and having also a laterally extended horn member with an illuminated switch control case thereon and switches therein positioned over the steering post head.
2. A switch control case for automobiles adapted to be supported by the steering post at one side thereof, and having switches therein operable in the same general plane as the steering wheel and having also a laterally extended horn member with an illuminated switch control case with switches therein positioned over the steering post head.
3. An operating control device for automobiles comprising a base, a housing, switches arranged marginally of the base with their ends in the same vertical plane, and a swinging angular lock member on the base for securing the several parts in 45 position.
4. The switch control case for automobiles comprising a base, a housing therefor, a plurality of pivoted switches, a plurality of sliding switches, each switch member adapted to project one end into locking position, and a lock for securing the switches in said position.
5. An operating control mechanism for automobiles comprising a base, a housing thereon, a pivoted switch member, a sliding switch member, a rotary switch member, the sliding and pivoted switch members con-

structed and arranged to project one end into locking position and a joint switch locking member for so securing the switch 60 members.

6. An operating control mechanism for automobiles comprising a base, a housing thereon, a lock for securing the housing to the base, a pivoted switch member, a sliding switch member, a rotary switch member, the sliding and pivoted switch members constructed and arranged to project one end into locking position and a joint switch locking member for so securing the switch members. 70

7. An operating control mechanism for automobiles comprising a base, a housing with an illuminated chamber thereon, a lock for securing the housings to the base, a pivoted switch member and a sliding switch 75 member in one housing constructed and arranged to project one end each into adjacent positions, a swinging locking member to lock said switch members in said positions, and a signal switch in the chamber 80 with illuminating means therefor.

8. An operating control mechanism for automobiles comprising a base 1, housings 2, 47, thereon, a pivoted switch 10 and push switch 9, sliding switches 7, 8 in one housing 85 and the angular locking member 39 therefor, the switch member 53 in the second housing and signal circuits 54—55, 56—57, 58—59 and 60—61, in said housing and illuminating means 62 therefor. 90

9. A car operating control mechanism comprising a base, a housing therefor, a lock therefor, a chamber in said housing, illuminating means within the chamber, a plurality of switches in the housing, certain ones 95 constructed and arranged to work at right angles to the others, and a common locking member therefor, and a rotary switch member above the illuminated chamber.

10. A car operating mechanism comprising a base, a housing with a lock therefor on the base, a chamber in the housing, illuminating means within the chamber, a switch member above the chamber, a plurality of switches in the housing, part of which 105 are constructed and arranged to work at right angles to the others and a joint locking member for locking the switches in the plane where the operating path of some of the switches crosses the operating path of other 110 switches.

In testimony whereof, I have signed my name to this specification.

EDGAR J. MARTEL.
